UNITED STATES PATENT OFFICE.

LEBRECHT STEINMÜLLER, OF GUMMERSBACH/RHEINLAND, GERMANY, ASSIGNOR TO
THE FIRM L. & C. STEINMÜLLER, OF GUMMERSBACH/RHEINLAND, GERMANY.

CLEANING DEVICE FOR MOVING GRATES.

Application filed April 27, 1926, Serial No. 105,010, and in Germany April 4, 1925.

In moving grates it is essential to keep the air apertures between the fire-bars free from clinker and ashes, so as to ensure a uniform and continuous supply of air for combustion. 5 It has already been sought to ensure this through a hammer action, which strikes against the travelling furnace bar moving upwards at the front end of the grate, in order to loosen the pieces of clinker by means 10 of the shaking action and cause them to fall. Such a hammer action causes a loud noise and destructive action, so that the result is that the furnace bars are injured by the hammering, and the working of the device is 15 not efficient. It has also been proposed to break up clinkers above the horizontal span of the grate by reciprocating bars arranged immediately above the grate, but such devices do not act at the most effective location 20 for removing clinkers and ashes and further are quickly destroyed by heat within the burning bed of fuel.

According to the invention the cleaning device is so constructed, that it gives the 25 furnace bars, which as usual are not fixedly mounted in their supports, a to-and-fro swinging motion, that is to say, a shaking motion. This shaking motion can be produced by blows against the furnace bars, 30 but the blows required are in no way greater, so that the danger of destruction of the furnace bars and the production of an excessive noise is avoided. The swinging or shaking motion of the furnace bars effects by continual repetition a loosening and breaking-up 35 of the clinker and ashes fused or collected together between them, so that the latter are released and fall through the bars.

Several constructional examples of the object 40 of the invention are shown in the drawing:

Figs. 1 and 2 show a constructional form partly in side and partly in end elevation.

Figs. 3-6 show a second constructional 45 form, in which only the particular parts are shown, which are necessary for the understanding of the invention.

In Fig. 1, *g* is the front grate drum, on which two straight furnace bars *f* are diagrammatically shown, which are carried on cross-bearers *f'* in known manner. In front 50 of the grate and within the casing *z* is provided a double-armed lever *a* universally mounted on axles *b* and *c* at right angles to

each other, a spring *d* acting on the lever *a* 55 at an angle so that it seeks to move it simultaneously towards the wall *z* and, as seen in Fig. 2, towards the left, so that a pin *i* located at right angles at its lower end is held in contact with a toothed disc *k*. A 60 similar double-armed lever is also provided at the other side of the grate, both levers being provided above with a transverse guide *h* extending across the breadth of the grate. Above the links *b*-*c* is provided on the 65 double-armed lever *a*, a roller *e* as an operating device. The furnace bar *f* on its rotatory movement presses by means of the roller *e* the upper arm of the double-armed lever *a* against the pressure of the spring *d* 70 so far back, that it can pass under the guide *h*. When therefore the furnace bar has passed the roller *e*, the roller falls and the parts take the position of Fig. 1, that is to say, the guide comes in position against the 75 upper part of the straight furnace bars. By this means there results a knocking or pushing action, which effects the loosening of the 80 ashes and clinker already collected on the furnace bars. During the further motion of the furnace bar *f* under the guide *h*, the double-armed lever *a* will now receive a to-and-fro motion from the toothed disc *k*, which for that purpose is set in rotation 85 from the driving gear for the moving hearth, as shown by the double arrow in Fig. 2, and thereby the guide *h* engages the furnace bars *f* on their left hand edges as regards Fig. 1; the furnace bars 90 are also given a to-and-fro movement round their supporting point on the guides *f*, and this motion is effected by the employment of teeth on the wheel *k*, as shown in Fig. 2 of different shapes, for example, sharper in one direction than in the other. The shaking motion thus obtained can be 95 varied according to the shape and number of the teeth, the speed of rotation of the wheel *k* and so forth.

The guide *h* strikes sideways against the furnace bar frame when the roller *e* ceases to contact with the furnace bar *f*, whereby the double action can be effected. But because the double action is in itself sufficient, the operation may be arranged by means of the roller *e* or some similar mechanism so that there is no blow given by the guide *h* 100 overhead. It is naturally not a necessity that 105

the roller *e* should be actuated from the furnace bars, for a curved disc located somewhere on the spindle of the drum *g* of the grate could also be used and there is then 5 the option whether the guide *h* shall operate on the furnace bars by a shock of any desired strength or without a shock.

In the constructional examples according to Figs. 3-6 a guide corresponding to the 10 part *h* of Figs. 1 and 2 is completely lacking.

In Fig. 4 a shaft or rod *t* is located before the front grate drum *g*; on this single elements *u* are provided, which have the shape of a one-arm lever with curved surfaces on the part adjacent to the hearth or the furnace bars *f*. The elements *u*, which are arranged closely against each other on the rod *t*, are rotatable thereon, so that they may rest by means of their own weight 15 against the furnace bars *f* (Fig. 4). Their motion against the travelling hearth is limited by projections *v* and *w*, which are located partly on the arms *u* and partly on the grate rods *t*.

20 During the drive the rods *t* receive a to-and-fro motion in the direction of their own axes and carry therewith the arms *u* located thereon: the latter, which for the purpose are provided with serrated or similar edges as shown in Fig. 6 resting on the furnace bars *f*, effect thereby the above-described swinging or shaking movement.

25 A device corresponding to the roller *e* as provided in Figs. 1 and 2 for the double-armed lever *a* is not necessary, because the arm *u*, which can swing towards the right, referring to Fig. 4, only until contact is made with the projections *v* and *w*, engages 30 under each set of furnace bars and automatically is brought into the operative position as shown in Fig. 4.

An example of a drive for the rod *t* is shown in Figs. 3 and 5. From the grate 45 drive, a crank *o* with its shaft *p* is set in oscillatory motion through a connecting rod *n* and a gear indicated by *m*. On the shaft *p* is located as shown in Fig. 5 at both sides of the moving grate a double-armed lever *g*, which is connected through rods *r* with an 50 upper double-armed lever *s*, which is provided with threads engaging with corresponding threads formed on the end of the shaft *t*. The double-armed lever *s* is of course so arranged, that it cannot move in an axial direction. The double-armed lever *s* is thus set in oscillatory motion from the grate drive (or this could be effected in another manner) and this gives the shaft *t* an axial reciprocatory motion with the above-described result. The drive of the double-armed lever *s* or some equivalent part can naturally either be effected from the gear *m* or directly, if the dimensions, conditions and 60 so on of the moving grate furnace permit. The particular drive in Figs. 3 and 5 is 65

chosen on the assumption that space, through the detached toothed wheel mechanism, for the driving of the moving grate is limited. The shaft *t*, which carries the arms *u*, must of course be so placed, that it can move freely 70 in the direction of its axis, but is not rotatable.

Having now particularly described and ascertained the nature of my invention and in what manner the same is to be performed, 75 I declare that what I claim is:—

1. A cleaning device for a moving chain grate having laterally shiftable links consisting of a transverse bar disposed beyond the rear end of the grate surface and contacting the peripheral surface of the grate as it passes around the end of its path, and means to move the bar transversely over the surface of the grate as it is held thereagainst, whereby the links are cleaned on their outer 80 surface and moved apart to clean the spaces between them.

2. A cleaning device for a moving chain grate having laterally shiftable links comprising in combination a transverse bar disposed beyond the rear end of the grate surface and contacting the peripheral surface of the grate as it passes around the end of its path; a pivot for said bar to permit it to move toward and away from the grate, said bar being normally biased against the surface of the grate, and means to give the bar a substantially reciprocating movement over the surface of the grate.

3. A cleaning device for a moving chain 90 grate comprising in combination a shaft which is movable axially but is secured against rotation, a lever having screw threaded relation with the shaft which is free to swing but which cannot move axially, means connected to the lever to move it to cause endwise movement of the shaft, and a cleaning member swingably and non-slidably mounted on the shaft, said member being biased toward the surface of the grate 95 and being moved transversely over the surface of the grate by the movement of the shaft.

4. A cleaning device for a moving chain 100 grate comprising in combination a shaft which is movable axially but is secured against rotation, a lever having screw threaded relation with the shaft which is free to swing but which cannot move axially, means connected to the lever to move it to cause endwise movement of the shaft, and a cleaning member swingably and non-slidably mounted on the shaft, said member being biased toward the surface of the grate 110 and being moved transversely over the surface of the grate by the movement of the shaft, said member having a serrated surface 120 in contact with the grate.

In testimony whereof I affix my signature.

DR. LEBRECHT STEINMÜLLER.
